UNITED STATES PATENT OFFICE.

LOUIS ROSENFIELD, OF BALTIMORE, MARYLAND.

MEASURING AND DISPENSING APPARATUS.

Application filed February 16, 1921. Serial No. 445,379.

To all whom it may concern:

Be it known that I, LOUIS ROSENFIELD, a citizen of the United States of America, and resident of Baltimore, in the State of Maryland, have invented certain new and useful Improvements in Measuring and Dispensing Apparatus, of which the following is a specification.

This invention relates to measuring and dispensing apparatus and particularly to a valve controlled float, and novel means associated therewith for adjusting the float or setting it in order that it will operate the valve when a predetermined level of liquid is delivered to the receptacle in which the float is suspended, the said valve being effective to interrupt the discharge of air from within the receptacle and maintain a pressure which will prevent the entrance of additional liquid when a predetermined level is reached.

A further object of this invention is to provide a combined float and valve stem, the said stem being adjustable within the valve and effective to support the float at different positions within the receptacle so that when liquid has reached a level to raise the float, the valve will be closed.

A still further object of this invention is to provide a float and valve stem of the character indicated having graduations which will permit the valve stem to be set for closing the valve when a predetermined amount of liquid has been delivered to the receptacle.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which—

Figure 1 illustrates a sectional view of a receptacle having a valve controlling mechanism embodying the invention applied thereto;

Figure 2 illustrates an enlarged sectional view in detail of the valve and parts associated therewith; and

Figure 3 illustrates a sectional view on a line corresponding with the line 3—3 of Figure 2.

In these drawings 5 denotes the measuring receptacle having delivery and discharge pipes 6 and 7 respectively, the former of which admits the fluid to the receptacle and the latter of which permits the fluid to discharge from the said receptacle. The discharge pipe has a strainer or guard 8 associated with it, which is disclosed in a former application, and need not, therefore, be described in detail.

The receptacle 5 has a flanged opening 9 threaded as at 10 to receive a cover or closure 11, the said closure having an apertured central boss 12 forming a guide for the sleeve 13, the lower end of which terminates in a valve 14. The sleeve at its upper end is supplied with a ring nut 15 which limits the downward movement of the said sleeve, since the ring nut will abut the upper end of the hollow boss and the said sleeve has apertures or vents 16 through which air may be discharged from the interior of the receptacle.

The valve 14 has a threaded aperture 17 in which the valve stem 18 is threaded for adjustment and the said valve stem supports a float 19 through its connection with the float as shown in Figure 2 of the drawing. A jam nut 20 is threaded on the valve stem and is employed for engaging the lower end of the valve when the parts have been properly set and it will prove effective in preventing a change of position of the valve stem when the device is being operated.

The valve stem has graduations 21, the standard of which may represent quarts or gallons and the valve stem may be properly set with relation to the upper end of the sleeve to denote the capacity of the tank when the float is suspended within the tank at the position indicated by the number of the graduations.

The cover or closure 11 has its inner surface shaped to form a valve seat 22 with relation to which the valve is movable and hence when the float raises the valve into engagement with the valve seat, the air vents or apertures 16 are sealed and air cannot escape from the receptacle. When such a condition arises, the pressure within the tank will prevent the entrance of fluid and the amount of fluid indicated by the number exposed on the valve stem will be contained within the receptacle. At such time, the contents of the receptacle may be discharged and the float will gravitate for a renewal of

the operation, and the receptacle may be alternately filled and emptied for the delivery of a quantity of fluid indicated.

I claim—

5. In a valve for controlling the displacement of air within a receptacle, a sleeve slideable in an aperture of the receptacle in relation to and operative with a valve seat at said aperture, a valve forming a part of said

sleeve adapted to coat with the valve seat, 10 means for preventing disassociation of the sleeve from said receptacle, a valve stem threaded through the valve and situated in spaced relation to the sleeve, the said sleeve having air discharge orifices at the junction 15 of the valve and sleeve, and a float carried by the valve stem.

LOUIS ROSENFIELD.
